UNITED STATES PATENT OFFICE

123,694

DESIGN FOR A COMBINED ASH CONTAINER AND TRAY

Henning Huebinger, Springfield, Ill.

Application April 1, 1940, Serial No. 91,409

Term of patent 14 years

To all whom it may concern:

Be it known that I, Henning Huebinger, a citizen of the United States of America, residing at Springfield, in the county of Sangamon and State of Illinois, have invented a new, original, and ornamental Design for a Combined Ash Container and Tray, of which the following is a specification, reference being had to the accompanying drawing, forming a part thereof.

The figure is a perspective view of a combined ash container and tray showing my new design.

I claim:

The ornamental design for a combined ash container and tray, as shown.

HENNING HUEBINGER.
